[57] ABSTRACT

A hair curl fastened near the scalp on a curler or roller by a flexible band extending from one end of the roller to the other is held in close proximity to the head by passing a flexible pick between the roller and the band and between the roller and the scalp. Such a pick can be made of white nylon and includes a soft, flexible shank having either a blunted or rounded or pointed outer end, a shoulder extending integrally normally from the other end of the shank, and a finger piece integral with the shoulder opposite the shank. The presence of the shoulder on the shank provides an increasing stiffness of the shank toward the shoulder end of the pick. Notch is provided in the shoulder-shank portion of the pick opposite the finger piece and near the end of the shank in position to receive the flexible band to prevent it from slipping off of the shoulder shank.

FIG. 4

HAIR WAVING PICK

BACKGROUND OF THE INVENTION

Waving picks for passing between the roller and the scalp were not in common use before the development of my method as set out in my copending application for a METHOD OF WAVING HAIR, Ser. No. 796,801, filed Feb. 9, 1969; but picks have been designed for use with other hair curlers, and particularly with the so-called brush type curler and with plastic curlers of open construction. These picks are designed to pass clear through the curler itself to hold the hair section in place thereon. Such picks must be of sufficient rigidity and size to be strong enough and sharp enough on the outer end to easily penetrate the curler or roller and to hold their position in the brush type roller or open plastic roller.

Such picks would be completely unsuitable for use between the roller and the flexible roller band and between the roller and the scalp. Specifically, where the diameter of the shank of the pick is thicker than the thickness of the wrapped hair section between the roller and the scalp, the roller will be forced away from the scalp by the presence of the pick and the resulting wave will be imperfect to the extent that the hair is not curled near the scalp. Further, such a forcing of the roller away from the head will tend to get in the way of the next roller as the operator continues the rolling process. It will also cause unnecessary and dangerous stress on the hair follicle and will cause discomfort to the user. Picks of the prior art designed to be forced through rollers are of approximately twice the diameter of a pick of the present invention and are about twice as long.

SUMMARY OF THE INVENTION

A pick made according to the present invention includes a soft, elongated flexible outer shank having either a blunted or rounded or pointed outer end, the shank merging at the end opposite the outer end into an integral shoulder which extends outwardly from the shank at approximately right angles thereto. A flat or three dimensional finger piece is integral with the end of the shoulder opposite the shank, and a safety notch is provided in the shank where it is integral with the shoulder in position to receive the flexible band to prevent it from slipping off of the end of the shoulder-shank portion of the pick. After the hair from a particular hair section of the scalp is rolled onto a hair curler or roller until it has position immediately adjacent the scalp, a flexible band is supported on each of the opposite ends of the roller and is situated in adjacent relationship to the scalp and in holding relationship to the hair curl positioned on the roller. A pick of the present invention will then be grasped at the finger piece by an operator, and the outer end of the pick will be forced between the flexible band and the roller, through a central portion of the hair curl between the roller and the scalp until the shoulder and finger piece come to rest against the roller. The shank and shoulder hold the flexible band, and hence the attached roller, in close proximity to the scalp, the distance from the scalp being determined by the bulk of the hair curl between the roller and the scalp and by the diameter of the pick. The stiffness of this shoulder-shank portion will cause the roller to be maintained in its closest relationship to

the scalp, while the flexible outer end portion of the shank will conform to the shape of the scalp and will lie easily against the scalp so that it will not be in the way of work done on adjacent hair sections.

BRIEF DESCRIPTION OF THE DRAWING

FIG. 1 is a rear view of a head showing a typical pattern of natural growth direction of the hair thereon and showing several hair curls held in place by picks made in accordance with the present invention;

FIG. 2 is an enlarged sectional view taken on the line 2—2 of FIG. 1;

FIG. 3 is an enlarged view taken on the line 3—3 of FIG. 1; and

FIG. 4 is a combined end view and side elevational view of one pick made in accordance with the present invention.

DESCRIPTION OF PREFERRED EMBODIMENT

Referring to the drawings of the numerals as reference thereon, a head, indicated generally at 10, is seen to have hair 11 thereon extending therefrom in its natural growth direction, starting at the crown (cowlick) area 12 and extending outwardly in all directions. As seen in FIGS. 1, 2 and 3, a number of curls 17 are disclosed as having been wound around hair curlers or rollers 22 until the rollers are as close as possible to the roots of the hair and the hair sections that have been rolled to form the curls. A flexible band or strap 25, fastened over one end of the curler 22 is then fastened over the second end of the curler 22 to encompass the hair curl on the rod and hold it in place as best seen in FIG. 3. Next a pick 27 of the invention having a finger piece 31 and a shank 33 with an outer end 32 is introduced between the roller 22 and flexible band 25 and the shank is slid along the scalp until the pick has positioned substantially as seen in FIG. 2.

As to the construction of the pick itself, as best seen in FIG. 4, the shank 33 will be soft and flexible and of uniform diameter over most of its length, but toward the end opposite the outer end 32, the shank connects to an integral shoulder 34 which extends outwardly from the shank 33 at substantially right angles thereto. A fillet 40 at this connection adds stiffness to a shoulder-shank portion 35 of the pick and thereby allows or permits the pick to hold the flexible band 25 and thus the roller 22 and curl 17 in a position as close as possible to the scalp of the head 10, as best seen in FIG. 2. It is advantageous if this stiffness, or at least a part of it, extends downwardly along the shank from the shoulder 34 a distance at least equal to the diameter of the particular roller being used.

A notch 36 is provided in the shank face side of the shoulder-shank portion 35, and is for the purpose of intercepting the flexible band 25 to keep it from slipping up over the top of the shoulder and thus at least partially releasing the roller being held by the pick. In actual usage, many times this flexible band 25 will not rest in the notch 36, but will rest along the shank face of the shoulder-shank portion at a side of the notch away from the top of the shoulder. Then, if and when the roller becomes misplaced or dislodged as it is worn in the hair, the flexible band will not slide any further than into the notch 36.

When the hair wave has been set, or whenever the curlers are to be removed, each finger piece 31 can easily be reached by the operator and the pick withdrawn. The band 25 will then be removed from the roller, and the roller removed from the curl in any usual or preferred manner. While the finger piece 31 is shown to be flat, it is to be understood that it could be in the form of a spheroid or in any other convenient three dimensional form.

The shank 33 of the picks seen in the drawings, has been shown to be relatively short, so that each pick is used to position only one particular curl 17 and roller 22. However, it is to be understood that the picks or some of them could be longer. In that case, a particular pick could be used to position more than one roller, in the manner as set out in my copending application, above identified. Picks of the present invention can be made of white nylon, but many other substances will also have the necessary and desirable properties.

In order that the pick not contribute to the holding of the roller and hence the curl away from the head unnecessarily, it is desirable that the diameter of the shank of the pick be no greater than the thickness of the hair of a particular section which is situated between the roller at the point where the pick passes

adjacent the roller and the scalp.

The embodiments of the invention in which an exclusive property or privilege is claimed are defined as follows:

5. 1. For use with a head supported hair curl on a hair waving roller and a band fastened to end portions of said roller to hold the curl on the roller, a pick for holding the roller in close proximity to the head by passing at the same time between said band and said roller and between the head and said roller, said pick including an elongated shank having an outer end portion, a shoulder extending outwardly from an end of said shank opposite said outer end portion at substantially right angles to the shank and a finger piece integral with said shoulder at a side thereof opposite said shank; said elongated shank being of flexible material of uniform transverse dimension over the major portion of its length but having a fillet connecting it to said shoulder, said connection being such as to increase the stiffness of the shank adjacent the shoulder; and wherein said shank is provided with a notch in adjacent spaced relationship to the edge of said shoulder opposite said outer end portion of said shank.
